Des. 181,520
Patented Nov. 26, 1957

181,520

EMBOSSED METAL SHEET MATERIAL

John W. Ebstein, Roslyn Heights, N. Y., assignor to
Rigidized Metals Corporation, Buffalo, N. Y.

Application October 24, 1956, Serial No. 43,501

Term of patent 14 years

(Cl. D54—2)

FjQ.1.

FjQ.2.

Fig. 1 is an elevational view looking directly at the face of an embossed metal sheet material showing my new design; and

Fig. 2 is a cross-sectional view on either of the lines 2—2 of Fig. 1.

I claim:

The ornamental design for an embossed metal sheet material, as shown.
